Patented June 25, 1929.

UNITED STATES PATENT OFFICE.

YASABURO MORIMOTO, OF LOS ANGELES, CALIFORNIA.

VEHICLE TRAFFIC SIGNAL.

Application filed June 25, 1928. Serial No. 288,135.

This invention relates to automobile signals, and its object is to provide such a signal which is effective in operation and cheap to manufacture.

In carrying out my invention, I provide a bracket adapted to be secured to the side of an automobile, a casing pivotally connected to the bracket, a lazy-tong projecting mechanism adapted to be extended from the casing, a fabric signal carried by the lazy-tong mechanism, elements for actuating the lazy-tong mechanism, and means for illuminating the fabric signal when in the display position, the mechanism including means for shifting the signal to angular indicating positions after it has been projected from the casing.

The invention is directed particularly to an improvement in traffic signals, and particularly to a specific operating means in connection with a traffic signal described and claimed in United States Patent, No. 1,567,539, issued to me on the 29th day of December, 1925.

It is my purpose to provide a device of the type set forth which will embrace the desired features of simplicity, efficiency, and durability, which will effectively display the desired signals, and wherein the component parts are so arranged as to reduce the possibility of derangement to a minimum.

It is to be understood that the structural embodiment of the invention as a whole and its various features as shown is merely illustrative and not restrictive. I therefore do not desire to be limited in these particulars except as set forth in the appended claims.

In the drawings: Figure 1 is a longitudinal and sectional view of a signal device embodying the features of the present invention. Fig. 2 is a front elevation of the signal housing. Fig. 3 is a side elevation of the signal housing, and shows a portion of the supporting means. Fig. 4 is a plan and sectional view of the signal housing and actuating mechanism. Fig. 5 is a rear elevation of the device. Fig. 6 is a diagram of the wiring and electric elements.

Referring to the drawings in detail, the housing 15, has a cover 16, and front apertures 17 and 18, the apertures 18 being provided with transparent closures 19. Housing 15, has a U-shaped supporting member 20, on the back thereof, and has inner partitions 21. A U-shaped supporting member

22, pivotally connected with member 20, is adapted to be secured to bracket 23, or to some portion of the automobile.

Partition members 21, divide the interior 60 into compartments 24 and 25. Within compartments 24, I provide reflectors 14, and in compartment 25, I provide rollers 26. An articulate member 27, of lazy-tong construction, is mounted in compartment 25; 65 its inner elements 28, being pivotally connected on pivot members 29, and its outer elements 30, pivotally connected to member 31, on bar 32. Fabric element 33 winds on rollers 26, and has its central part connected to bar 32. Rollers 26, are operatively mounted on fixed shafts 34, and are actuated by springs 35, each spring having one end fixed to the shaft and the opposite end to a roller. A plunger 36 is connected at one 75 end to the movable semaphore elements by a pivotal element 37, and slides through a crosshead 38, integral with member 20. The plunger has on the opposite end the pivot 39.

The sliding movement of plunger 36, outwardly, actuates the semaphore to display position, the same being projected horizontally from the housing. For actuating the plunger, I provide a link 40, slidable 85 through rotative member 41, which has fixed thereto a bracket 42, having a pivotal extremity 43, to which is connected the operating handle 44. A rotatable but non-slidable crosshead 45 is mounted on link 40, 90 and links 46 connect the extremity 47, of handle 44, with crosshead 45. Member 41 is rotatably mounted in member 22 and in a corresponding member 48. On the opposite end of member 41, I provide a gear 49, constantly in mesh with gear 50, fixed to member 20. Movement of the handle 44, serves to actuate link 40, and plunger 36, thereby actuating the semaphore to display position. Movement of the handle, with reference to 100 the axis of member 41, serves to actuate the semaphore to angular display positions relative to its initial display position.

The semaphore is adapted to be illuminated both by day and by night. Means for accomplishing this, consist of incandescent bulbs 51, mounted in compartments 24. Electric conductors 52 and 53 are connected to suitable grounds and to battery 57, and to bulbs 51, whereby the bulbs are energized. 110 A switch 54, mounted on bracket 42, is interposed in conductor 52, and has a plunger

55, actuated to closed position by cam 56, depending from handle 44, the cam becoming operative as the semaphore approaches its display position. Switch plunger 55 is 5 spring-actuated to inoperative position when released by cam 56. For determining the operative positions, handle bracket 43 is provided with slideable plunger 58, actuated by spring 59, and adapted to engage with recesses 60, 61 and 62, in member 48. Projections 64 serve to limit movement of handle 44 in either direction. The fabric element 33, may be colored as desired, being preferably a red color.

15 In use, the operator first shifts the handle to project the semaphore outwardly from the housing. This movement closes the switch, thereby illuminating the semaphore. Should other signals be desired, the operator shifts the handle through a vertical arc of movement, thereby shifting the semaphore to upwardly or downwardly inclined positions.

From the foregoing description and drawings, it may be seen that I have provided a 25 simple and efficient device for displaying traffic signals adapted for motor vehicles, and for other purposes.

What is claimed is:

1. In combination, a housing, a supporting bracket, a pivotal connection between the housing and supporting bracket whereby the housing may be shifted to angular positions in a vertical plane, collapsible semaphore elements mounted within the housing, a 30 plunger connected to the collapsible elements, a fabric semaphore element connected to the 35

collapsible elements and actuated thereby to display position, rollers disposed in the housing, said fabric element being connected to the rollers, springs arranged to actuate the 40 rollers whereby to wind up the fabric element, a member rotatively mounted relative to its supporting means, a link slideable through the rotative member, a bracket fixed to the rotatable member, a handle pivotally 45 connected relative to the bracket, a crosshead on the slideable link, other links connecting the crosshead and handle, said slideable link being pivotally connected to said plunger, a gear connection between the said rotatable 50 member and said housing, and means for limiting the rotary movement of said rotatable member.

2. A supporting bracket, a casing operatively connected thereto, and movable 55 through a vertical and arcuate path of movement, a collapsible lazy-tong mechanism mounted in the casing, means for projecting the collapsible mechanism from the casing, including a handle, a plunger connected to 60 the lazy-tong mechanism, and a link connecting the handle and plunger, a fabric element connected to the collapsible mechanism, rollers mounted within the casing, said fabric element being connected to the rollers, 65 springs to actuate the rollers whereby to wind the fabric thereon, and other mechanism operated by said handle, whereby to actuate said casing.

In testimony whereof I hereunto affix my 70 signature.

YASABURO MORIMOTO.
